UNITED STATES PATENT OFFICE.

EDWARD C. SCHENK, OF NEW YORK, N. Y., ASSIGNOR OF ONE-HALF TO EDMUND V. CARLSEN, OF NEW YORK, N. Y.

THREAD TIP.

Application filed August 2, 1923. Serial No. 655,369.

To all whom it may concern:

Be it known that I, EDWARD C. SCHENK, a citizen of the United States, and a resident of New York, in the county and State 5 of New York, have invented certain new and useful Improvements in Thread Tips, of which the following is a full, clear, and exact specification.

This invention relates to stiffened thread 10 tips designed to avoid the necessity of using needles for threading beads, gems or the like.

In order to thread beads or gems upon a silk cord in the ordinary manner a needle 15 is required for conducting the cord through the eyes or passages in said beads or gems, and as said eyes or passages are often of irregular size, many valuable beads or gems have been destroyed as the result of trying 20 to force a needle therethrough. Sometimes the eye in a bead is barely large enough to permit the passage of the needle, but the protruding portions of the cord threaded through the eye of the needle obstruct said 25 eye and results in the cutting of the cord. By forming a stiffened tip on the end of the cord, the use of a needle is rendered unnecessary and the breaking of beads and cutting of the cord in the ways just mentioned are avoided.

A special object of this invention is to provide a stiffened thread tip which will not be apt to fray out at the end. When 30 a twisted silk cord, such as is generally used for threading beads and gems, has its end simply hardened or stiffened, as has heretofore been done, the ends of the strands of cord will soon fray out after being threaded through a number of beads, and it is obvious that when so frayed the end of the tip will obstruct the passage of the cord through the eyes of the beads and greatly interfere with, or completely prevent, the further use of said cord. This fraying of 40 the end of the tip is eliminated in the present invention by folding back a substantial portion of the thread upon itself and twisting said overlapping portions together before the stiffening agent hardens the tip.

The invention will be first hereinafter described in connection with the accompanying drawings, which constitute part of this specification, and then more specifically defined in the claims at the end of the description.

In the accompanying drawings, wherein similar reference characters are used to designate corresponding parts throughout the several views:

Figure 1 is an enlarged view of the end 60 portion of a threading cord having a stiffened tip formed thereon substantially in accordance with this invention.

Figure 2 is a similar view showing an intermediate stage in the formation of the 65 tip.

Figure 3 is a similar view of a cord having a modified form of stiffened tip.

Figure 4 is a view of the same form of tip shown in Figure 3 but illustrating how 70 the ends of the tip becomes frayed in use.

Referring first to Figures 1 and 2 of the drawing, 1 designates an ordinary twisted silk cord such as is used for threading beads and gems for making necklaces. In forming the stiffened tip 2 on said cord, the end portion 3 thereof is folded back, as illustrated in Figure 2, and the overlapping portions are then twisted as shown in Figure 1. The portion of the thread from 80 which the tip is formed is saturated with a suitable stiffening liquid, such as a solution of starch, gum arabic, shellac, or glue, which will harden when exposed to the atmosphere, before the extremity 3 is folded back 85 upon the cord 1 preparatory to twisting the tip into the form shown in Figure 1. After the tip is thus formed, it is allowed to harden before the cord is used. When said tip has become hard and stiff, it will serve 90 to conduct the cord through the eyes or passages in beads or gems without the use of a needle and without causing said tip to fray at its end.

The end of the folded and twisted tip is 95 not apt to fray because the ends of the strands from which the cord is made are not disposed at the end of the tip in this construction, as they are in the form of the tip illustrated in Figures 3 and 4. In 100 the latter figures, the end of the cord 4 is simply saturated with the stiffening liquid and allowed to harden in forming the tip 5, so that the ends of the strands composing said cord are exposed at the end of the tip 105 and are apt to become frayed out, as indicated at 6 in Figure 4.

I claim:

1. A thread tip having its end portion folded back upon itself and the overlap- 110

ping portions twisted together, said tip being stiffened substantially as described.

2. A thread composed of twisted strands and having its end portion folded back upon itself, the overlapping portions being twisted together to form a tip, said tip being stiffened substantially as described.

3. A thread composed of twisted strands and having its end portion folded back upon itself, the overlapping portions being twisted together to form a tip, said tip being stiffened substantially as described, the end of the tip being thus formed by the fold of the thread and the ends of the strands

composing the thread being arranged at a 15 distance from said tip end.

4. A method of forming a thread tip, which consists in saturating the end portion of the thread with a stiffening mixture, folding the extremity of said saturated portion backward upon itself, twisting said overlapping portions together, and allowing said twisted tip to be hardened by the setting of the stiffening mixture.

In testimony whereof I have signed my 25 name to this specification.

EDWARD C. SCHENK.
